BABY GUM SOOTHER

Murry Herbst, 266-16 78th Ave.,
Floral Park, N.Y. 11004

Filed Mar. 11, 1970, Ser. No. 21,862

Term of patent 14 years

Int. Cl. D24—05; D21—02

U.S. Cl. D83—8

FIG. 1.

FIG. 2.

FIG. 3.

FIG. 4.

FIG. 5.

FIG. 1 is a perspective view of baby gum soother showing my new design;

FIG. 2 is a front elevational view thereof;

FIG. 3 is a top plan view thereof;

FIG. 4 is a rear elevational view thereof; and

FIG. 5 is an end view thereof.

I claim:

The ornamental design for a baby gum soother, substantially as shown.
